(57) CLAIM

The ornamental design for a contemporary register cover, as shown and described.

DESCRIPTION

FIG. 1 is a perspective view of the contemporary register cover showing my new design;

FIG. 2 is a top plan view of the register cover of FIG. 1, the opposite bottom plan view being the same as the top plan view;

FIG. 3 is a front elevation view of the register cover of FIG. 1, the rear elevation view being the same as the front elevation view;

FIG. 4 is a left side elevation view of the register cover of FIG. 1, the right side elevation view being the same as the left side elevation view;

FIG. 5 is a top plan view of a further embodiment of the register cover; and,

FIG. 6 is a top plan view of a still further embodiment of the register cover.
